UNITED STATES PATENT OFFICE.

WILLIAM WALTER HUDSON, OF SALT LAKE CITY, UTAH.

AUTOMATIC TRAIN STOP.

Application filed November 7, 1923. Serial No. 673,327.

To all whom it may concern:

Be it known that I, WILLIAM W. HUDSON, a citizen of the United States, residing at Salt Lake City, county of Salt Lake, and 5 State of Utah, have invented certain new and useful Improvements in Automatic Train Stops; and I do hereby declare the following to be a full, clear, and exact description of the invention, such as will enable others skilled in the art to which it app- 10 pertains to make and use the same.

The present invention relates to improvements in automatic train stops, and has for an object to provide an improved mechanical device for automatically closing the engineer's throttle valve should the engineer inadvertently run past a signal set against him and into a forbidden block.

The invention moreover contemplates the 20 provision of means for bleeding the air line whereby to apply the brakes immediately after the closing of the throttle to effect an automatic stop without regard to any manual actuation by the engineer.

25 The primary object of the invention is to produce a simple mechanical arrangement adaptable to existing types of locomotives without requiring any alteration in the throttle valve mechanism, the air brake 30 valve or other parts, and which will utilize the triple valve now employed although in a different relation and coupled in a novel manner.

Other objects of the invention are to provide 35 a compact installation for the purpose stated, which will be relatively inexpensive, positive in action, not apt easily to get out of order, and such as offers an unusual freedom of test by the inspector, and ready accessibility for adjustment and repair.

With the foregoing and other objects in view, the invention will be more fully described hereinafter, and will be more particularly pointed out in the claims appended 45 hereto.

In the drawings, wherein like symbols refer to like or corresponding parts throughout the several views,

50 Figure 1 shows in dotted lines fragments of a locomotive, and in full lines the improved device applied thereto.

Figure 2 is a similar view taken from the end of the locomotive and showing the semaphore actuating mechanism.

55 Figure 3 is a diagrammatic view with

parts in section, and on an enlarged scale showing the improved system.

Figure 4 is an enlarged side view of the throttle mechanism.

Figure 5 is an end view of the same.

Figure 6 is a section taken on the line 6-6 in Figure 4, and

Figure 7 is a longitudinal section taken through the automatic operating part of the throttle valve.

Referring more particularly to the drawings, 8 indicates generally a locomotive; 9, the main reservoir for compressed air kept under appropriate pressure by the pumps 10, and 11 indicates the usual train line. 15 The engineer's air brake valve is shown at 12, and the throttle lever at 13 carried pivotally by the bracket 14 and coupled to the throttle valve through the link connection 15.

In accordance with the usual custom, pipes 16 and 17 connect respectively the main reservoir 9 and the train line 11 with the engineer's air brake valve 12.

20 In accordance with the present invention, 80 tapped into these pipes 16 and 17 are pipes 18 and 19 entering the casing 20 of the triple valve. As shown more particularly in Figure 3, the pipe 18 runs directly to the main reservoir 9, and is not connected with the pipe 16 while a little different arrangement of piping is also made with reference 25 to the pipes 17 and 19, but the same principle prevails. The triple valve is in usual manner provided with a cylinder 21 in 90 which is fitted for reciprocation the piston 22 having the piston rod 23 coupled to the slide valve 24 in the slide valve chamber 25 which adjoins the cylinder 21. Air from the train line entering through the pipe 19 95 has free access to the upper surface of the piston 22, while air from the main reservoir 9 has access to the bottom surface of the piston 22 inasmuch as the pipe 26 connecting with the pipe 18 and with the triple 100 valve casing 20 is coupled to a duct 27 leading the pressure below the piston.

The valve chamber is provided with ports 28 and 29, the latter communicating with an exhaust port 30 open to the atmosphere. The 105 valve 24 is also traversed by a longitudinal duct 31 in communication at its lower end with the valve chamber 25 and adapted to register with the port 28 in the lowered position of the valve. The port 28 connects with 110

a pipe 32 leading to one end of a brake cylinder 33 in which is fitted for reciprocation the piston 34 upon the piston rod 35. A coil spring 36 wound about the piston rod 35 tends to urge the piston 34 toward the left as indicated in Figure 3 until the action is overcome by the pressure of air against the piston. The pipe 37 connects through the side wall of the brake cylinder 33, and a valve 38 is located in this pipe.

The piston rod 35 extends out beyond the brake cylinder and connects with an extension rod 39, which has a part adapted to engage the throttle to close the same.

15 This arrangement is shown more particularly in Figures 4 to 7 inclusive. The extension rod 39 is shown to have a lateral projecting lug 40 and a flat shoulder 41 adjoining but inwardly of the lug. The lug 40 is provided with a beveled under surface 42 adapted to move in the path of the upper rounded end 43 of a rod 44 guided by a metal strip 45 secured upon one face of the throttle lever 13, which is slotted as indicated at 46 for the passage of the pin 47, which connects the rod 44 to the latch rod 48 having the usual pivot handle 49 carried by the throttle lever 13. The latch rod 48 is on one side of the lever 13, and the rod 44 is upon the opposite side, although these parts are connected together by the pin 47 and a spring 50 acting on the pin 47 in the slot 46 urges the latch rod 48 into engagement with the toothed sector 51.

30 Referring again to Figures 1 and 3, a trip valve casing is shown at 52 having the trip valve 53. This trip valve casing connects with the pipe 26 and with a pipe 54 leading to the atmosphere. The valve is normally closed by the action of a spring 55 pressed pin 55 engaging beneath the same and urging the valve upwardly against its seat. The valve stem 56 projects beyond the casing and against the intermediate portion 45 of a trip lever which is pivoted to swing about either of two pins 58 or 59 at opposite sides of the valve stem 56. The trip lever is connected at its upper end with a link 60 and the link 60 is coupled to the upstanding arm 61 of a bell crank lever fulcrumed upon the bracket 62 and having a horizontal companion arm 63. A link 64 is coupled to the arm 63 and to an arm 65 upon a rock shaft 66 journalled in brackets 67 upon the top of the locomotive cab and having a crank arm 68 arranged in the path of a trip device adapted to be set by the semaphore arm 70, and such trip device being carried by the semaphore standard 71, as for instance, upon the brackets 72 carried by such standard. The trip device is connected with the semaphore arm as by the link 73 and the shaft 74 so that when the semaphore is set against the engineer, the trip 69 will be in the path of the crank arm 68.

A weight 78 is fixed upon the shaft 66. When the device is tripped this weight swings over center and causes trip-valve 53 to remain open. A handle 77 on the bell-crank shaft enables the engineer to re-set the apparatus to initial position.

In the triple valve the usual feed grooves are, of course, eliminated or filled in.

The action of the device is as follows: The train line 11 is charged in the usual way 75 to the required pressure, and this pressure communicates with the top portion of the piston 22 in the triple valve casing 20. The connection of the pipe 19 with the pipe 17 it will be noted is below the engine cut out 80 valve 75. The pipe 19 enters the triple valve casing by the tapped port to which the auxiliary reservoir is usually connected. The pressure from the main reservoir 9 is carried to the other end of the triple valve piston as already stated. The pipe 26, through which this connection is made, is screwed into the triple valve casing at the tapped hole to which the train line is usually connected and thus the main reservoir pressure 85 is upon the lower end of the triple valve piston 22.

90 When the trip valve 53 is opened by the action of the trip, the pressure beneath the triple valve piston 22 is released to the atmosphere through the pipes 26 and 54. The pressure in the train line 11 then comes into play above the piston 22 and drives the same downwardly causing the slide valve 24 to shift to a position where the duct 31 registers with the port 28, thus putting the train line pressure in communication with the brake cylinder 33 through the pipe 32. In this case, the triple valve moves into emergency position. The compressed air will 100 shift the brake plunger 34 to the right compressing the spring 36 and the plunger will move over until the port of the pipe 37 is unmasked, whereupon the pressure will be permitted to escape to the atmosphere 105 through this pipe 37 and past the valve 38. When the pressure has been sufficiently reduced to balance the pressure of the spring 36, the piston 34 will move back and lap the pipe 37, thus preventing any more reduction 110 in the train line pressure.

115 The action of the plunger 34 will close the throttle valve by the action of the extension rod 39 as indicated in Figures 4 to 7 inclusive. The extension arm 39 in moving to the right will first cause the beveled lower nose 42 to ride into contact with the upper rounded end 43 of the bar 44, thus depressing the bar 44 and with it the latch rod 48, which is coupled thereto by the pin 47. The latch is thus moved out of engagement with the toothed sector 51 and following this movement, the shoulder 41 comes into contact with the throttle lever 13 substantially in alignment with the throttle stem 15. The 120 125 130

throttle stem is thus pushed in a substantially straight line causing the closing of the throttle valve. If the throttle valve for any reason tends to slam shut and advances faster than the shoulder 41 is propelling the same, the end of the extension bar 44 will recede from the lug 40 thus permitting the latch spring 50 to cause a reengagement of the latch with the sector 51. The parts would thus remain locked until the advance of the lug 40 and the shoulder 41. When the apparatus is rested, it will leave the throttle valve closed and latched.

The apparatus is released by closing the trip valve 53. The engineer may do this manually as through a lever 77 conveniently located to his hand. When this trip valve 53 is closed, the main reservoir air quickly builds up the pressure on the lower side of the triple valve piston 22 forcing the piston up and closing the connection between the train line and the brake cylinder 33. The air in the brake cylinder becomes exhausted through the ports 28 and 29, which are connected by the slide valve 24 as shown in Figure 3, and the port 29 leads to the atmosphere through the port 30. The spring 36 returns the plunger 34 to its initial position at or near the left head of the brake cylinder 33. The throttle is thus released, but it is closed and latched. However, the engineer is free to open it. The pipe 18, which includes the valve 76 is small in diameter, and the valve 76 is a needle valve that can be regulated to a very nice degree so that when the trip valve 53 is open it will not prevent the pressure in the pipe 26 from lowering enough to trip the triple valve. Also, it will not drain the pressure down in the main reservoir 9 as the air-pump will supply air faster than it can leak out by this connection. Since the pipe 26 and the triple valve have together a relatively small volume, it will take only a small quantity of air to recharge up to the pressure of the main reservoir 9.

The train being made up as the engine comes out to the engine track, there can be a dummy semaphore such as is shown in Figure 2 always set to stop, so placed that the engine must pass it. An inspector can observe if the throttle closes properly, and if the proper reduction is made in the train line pressure. Then, when the engine is coupled to the train, the inspector can throw out the trip by hand, observe its action, and set the tonnage valve to the proper opening. The run may then be made without getting into a closed block, or at each order-station, the station-man can set his manual station-semaphore to stop. This will give frequent inspections. At the end of the run, the engine may again be obliged to pass under the engine track dummy semaphore and give the engineer a chance to report the condition of

apparatus at the end of the run. When the apparatus is tripped on a run, the engineer will immediately set his brake valve on lap, release the apparatus by moving a small hand lever through a quarter turn and then proceed as in a regular stop. When everything is clear, he can start up again in the regular manner.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a locomotive and a signal-set trip, of a reservoir for air pressure carried by the locomotive, a triple valve casing, a plunger therein subject at one side continuously to pressure from said reservoir and at the other side to pressure from the train line, a valve connected for movement with said plunger, a brake cylinder adapted to be placed in communication with the train line pressure by said valve, said valve also adapted to evacuate the pressure from said brake cylinder, a normally closed valve adapted to place the reservoir pressure side of said plunger in communication with the atmosphere, yieldable means for holding said valve closed, a lever for opening said valve, a rock shaft carried by the locomotive and mechanically coupled to said lever, said rock shaft having a portion normally disposed in the path of the signal trip, means for holding said rock shaft and coupled parts in thrown position after operation, and means for manually resetting the rock shaft and closing said last named valve.

2. In combination with a locomotive and a signal-set trip, of a reservoir for air pressure carried by the locomotive, a triple valve casing, a plunger therein subject at one side continuously to pressure from said reservoir and at the other side to pressure from the train line, a valve connected for movement with said plunger, a brake cylinder adapted to be placed in communication with the train line pressure by said valve, said valve also adapted to evacuate the pressure from said brake cylinder, a normally closed valve adapted to place the reservoir pressure side of said plunger in communication with the atmosphere, yieldable means for holding said valve closed, a lever for opening said valve, a bell-crank coupled to said lever, a rock shaft carried by the locomotive and having a crank portion adapted to strike the signal trip, a weight carried normally in the potentially inoperative position by said rock shaft for holding the rock shaft in thrown position, an arm on said rock shaft, a link connecting said arm with the

- arm of said bell-crank, and manual means for closing said last named valve and restoring the rock shaft and weight to potential position.
5. 3. In combination with a locomotive and a signal-set trip, of a reservoir for air pressure carried by the locomotive, a triple valve casing, a plunger therein subject at one side continuously to pressure from said reservoir and at the other side to pressure from the train line, a valve connected for movement with said plunger, a brake cylinder adapted to be placed in communication with the train line pressure by said valve, said valve also adapted to evacuate the pressure from said brake cylinder, a normally closed valve adapted to place the reservoir pressure side of said plunger in communication with the atmosphere, means carried by the locomotive operated upon by said signal trip for opening said last named valve, a plunger in said brake cylinder, an arm movable with said plunger and having a shoulder and a reduced beveled tip portion, a throttle valve lever in the path of said shoulder, a latch for the throttle valve, and a rod coupled to said latch and disposed in the path of the beveled tip on said arm.

4. In combination with a locomotive and a signal-set trip, a triple valve casing having a plunger chamber and a valve chamber therein, a plunger in said plunger chamber, a valve coupled to said plunger and disposed in said valve chamber, a valve casing separate from said triple valve casing, a pipe connecting the plunger chamber in said triple valve casing with said last mentioned valve casing, said last mentioned valve casing adapted also to communicate with the atmosphere, a yieldably closed valve in said last mentioned valve casing, means acted on by the signal trip for opening said last mentioned valve, a pressure reservoir, a conduit of smaller diameter than said pipe connected to said pipe between the triple valve casing and the last mentioned valve casing, means in said conduit to regulate the flow of pressure, a train line connecting with the valve chamber of said triple valve casing, and a brake cylinder also communicating with said valve chamber of the triple valve when the valve therein is in one position and with the atmosphere when the valve is in a subsequent position.

WILLIAM WALTER HUDSON.
